SWAB FOR TAPERED CASING OR TUBING

Howard J. Pankratz, Bartlesville, Okla., assignor
to Phillips Petroleum Company, a corporation
of Delaware

Original application March 11, 1947, Serial No.
733,881. Divided and this application March
23, 1951, Serial No. 217,239

8 Claims. (Cl. 103—225)

1

This invention relates to swabs. In one specific aspect it relates to swabs which are self adjustable to fit and operate properly in a plurality of dimensions of pipe such as the casing or tubing of a well.

This application is a division of my copending application Serial No. 733,881, filed March 11, 1947, now Patent No. 2,623,473 dated December 30, 1952, for "Swab for Tapered Casing or Tubing," and the claims herein are directed to that species of the invention shown in Figure 1 thereof.

In modern practice in deep wells, it is advantageous and economical to use tapered strings of casing and tapered strings of tubing, with thinner tubing or casing for the center portion of the well and increasing the thickness of the walls of the casing or tubing toward the top and bottom of the well. In inserting tubing and casing in a well it is suspended from the derrick in a long string thousands of feet in length and the center portion of the string need not be as strong as the upper portion, which is supporting the lower portion, or as strong as the bottom portion which must withstand the hydrostatic collapse pressure. By making the lower portion lighter, the upper portion has less to support. The only disadvantage of this system is that the inside diameter of the tubing or casing varies from small to large and back to small again as a swab travels up the well and the swab must adjust itself to the change in diameter. The tapering of the tubing is generally not uniform, but usually consists of running several hundred feet of a certain thickness, and then running a similar number of the next thickness, and then the next thickness, etc., until sufficient tubing or casing has been assembled.

During the life of a well it is often necessary to swab the same either as a simple pumping operation, or for other purposes such as causing pressure changes on the formation to stimulate natural flow, or simply to remove liquids or mud from the well.

While satisfactory swabs have been produced which will work with high efficiency for long periods of time in a single internal diameter size of tubing or casing, these swabs have proved inefficient, or inoperative, or have rapidly broken down when used with tapered casing or with tubing having a plurality of internal diameters.

One object of the present invention is to provide an improved swab.

Another object is to provide a simple and easily operated swab having a minimum number of

2

parts which are inexpensive to build and rugged in operation.

Another object is to provide a swab which will operate in a casing or tubing having a plurality of inside diameters.

Another object is to provide a swab which will automatically adjust itself to a wide variation in internal diameters of a pipe through which it is being pulled.

Another object is to provide a swab which uses the hydrostatic head of the liquid being lifted to seal the swab to the pipe.

Another object is to provide a swab which can be collapsed for easy removal upon dropping a weight.

Another object is to provide a swab which can be collapsed for easy removal by operation of a time clock.

Another object is to provide a swab which is inflatable by a self contained source of gas under high pressure.

Numerous other objects and advantages will be apparent to those skilled in the art upon reading the accompanying specifications, claims and drawings.

In the drawings:

Figure 1 is a cross sectional view with parts broken away of a swab embodying the present invention.

Figure 2 is a similar view of a second modified swab embodying the invention.

Figure 3 is a similar view of a third modified swab embodying the invention.

Figures 1, 2 and 3 show only a portion of the swab, the longitudinal axis of the swab running longitudinally of the figures right through the center of the large balls shown therein. As most of the elements of the swab are volumes of revolution generated around that axis, it is believed that illustration of the broken away portion of the swab is unnecessary.

In Figure 1, a swab generally designated as 4 is designed for operation in pipe of varying diameter in a well for swabbing liquid from said well. Swab 4 comprises a first supporting member 6 which is preferably made in two parts

6 and 7 in order to allow access to the interior thereof. At 8 threads are provided for connection with a cable or tubing by which the swab is raised or lowered in the well.

A second supporting member 9 is provided at telescopic relationship with said first member 6, and said member 9 is preferably made in several pieces, namely, body parts 9 and 10, plug 11 and cap 12. Cap 12 is provided with holes 13 and

acts to push washer 14. Plug 11 is provided with a passage 16 communicating with passage 17 in the interior of 9 and through passages 13 with passage 18 in the interior of 6 and then through passage 19 to the exterior of the swab. Passages 19, 18, 13, 17 and 16 form a by-pass passage around the swab 4 and flow therethrough is controlled by an upwardly opening check valve 21.

When the swab is first inserted in the well, washer 14 is held above frangible pin 22, but in the position shown in Figure 1, frangible pin 22 has been broken and the broken off portion 23 has fallen to rest on shoulder 24 of member 6.

Member 9 is provided with outstanding ears 26 to which arms 27 and 28 are pivoted by pivot pins 29 and 31 respectively.

Arms 27 and 28 have curved cam surfaces 32 and 33 respectively to engage rubber cup 34 and extend the same out to the tubing which is of varying diameter.

Cup 34 rests on flange 36 of member 10 and has a sealing flange 31 provided to prevent leakage. Cup 34 is held down by shoulder 38 which is spring pressed by spring 39. The upper edge of cup 34 is turned inward at 41 and is preferably secured to some form of retaining means such as ring 42 by means of such securing means as bolt 43 and nut 44. Ring 42 is provided with holes 46 and fits loosely around member 6 at 47.

Arm 27 may be provided with a cut away portion 48, if desired, as such cut away portion gives better action to the arm. Arm 27 is pivoted on member 9 at 29 and in effect is pivoted on member 6 at 49. While only one set of arms 27 may be used if desired it is preferred to have at least another set of arms such as 28. As many sets of arms as desired may be provided, each set being separated by a spacing sleeve 51 and urged apart by a spacing spring 52. The lower set of arms 28 is supported by a spring 39 and support member 53.

Inside of sleeve 51 is provided a space 54 and inside of cup 34 is a space 55 for the collection of liquid in the swabbing of the well as such liquid tends to expand cup 34 into sealing engagement with the well pipe.

In Figure 2, a modified form of swab, generally designated as 61, is shown having a supporting member 62 which is provided with means 63 at its upper end for connection to a cable or string of pipe by which said swab is operated upwardly and downwardly in the well.

Member 62 is provided with a central by-pass passage 64 communicating with the well through holes 66 above packer 67 and through hole 68 in plug 69 below packer 67. Flow through this by-pass passage is controlled by the upwardly opening check valve 71. Member 62 is provided with upper flange 72 and a lower flange or washer 73. Between flanges 72 and 73 are located the operating portions of the packer.

Packer 67 consists of an annular rubber tube or casing very much like an automobile tire in which is disposed an inflatable inner tube 74, which will expand into space 76 when gas under sufficient pressure is placed in space 77.

A chamber 78 is provided having a gas space 79 containing sufficient gas under sufficient pressure to inflate tube 74 and press casing 67 firmly against the wall of the well pipe, regardless of the diameter of the pipe. As the pipe decreases in diameter, part 67 will be correspondingly deformed and the air in 77 correspondingly compressed.

In order to connect space 79 with 77 a conduit 81 is provided connecting the two. Conduit 81 is controlled by an upwardly opening spring check valve 82 and a downwardly opening spring valve 83. Valve 83 is adapted to be compressed by arm 84 when body 86 is moved downwardly, conduit 81 being flexible at point 87 to allow for such movement. When the device is inserted in the well a flexible pin 88 holds conduit 81 in extended position. When flexible pin 88 is broken, however, due to the weight of liquid above 67, flexible pin 88 becomes broken and valve 83 is forced open.

Conduit 81 may be made up in a large number of ways and may comprise various nipples 89, 91 and 92 and thimbles 93 and 94. Nipple 92 contains valve 96 which may be open by contact of plate 97 with head 98. Plate 97 ordinarily cannot contact head 98 because springs 99 guided on pin 101 holds 97 spaced from top plate 102.

The flexible tube assembly 67 includes top plate 102 and lower plate 86 along with intermediate plates 103 and 104 held together by bolt 106. These plates allow the assembly of the device which otherwise would be hard to assemble, as conduit 81 has a branch 107 connecting to tube 74 by the usual connecting means 108 and 109.

A go-devil tube 111 is provided with a tapered surface 112 to avoid contact with flange 102. Go-devil 111 is dropped into the well to open the valve by plate 97 contacting valve 98 by compressing spring 99 when desired.

In Figure 3, a third type of swab, generally designated as 113, is shown. This swab is built into a single body composed of upper member 114 having threads or other means of connection 116 for connecting the same to a cable or operating tubing (not shown). Member 114 is screw threaded to sleeve 117 which in turn is closed by plug 118 having a passage 119 therethrough controlled by upwardly opening check valve 121. A by-pass conduit is provided at 122 in sleeve 117 with passages 123 below the packer casing 124 and passages 126 above the packer casing for passage of liquid around the casing.

Casing 124 is similar to an automobile tire casing and tube 127 is similar to an automobile inner tube. A guide plate 128 is provided for guiding the upper part of casing 124 and a lower flange 129 on body 117 guides the lower portion of the casing. A removable annular member or rim 131 is provided to enable the tires 124 and 127 to be disassembled.

When gas under pressure blows into chamber 132 inside tube 127, it forces tube 127 to expand through space 133 into contact with tube 124. The lower part of 117 is threaded to receive the lower body portions 134 and 135. Body portion 135 contains enough gas in 136 and enough pressure to actuate the inflation of tube 127. A time clock 137 in 134 may be wound up by winder 138 and shaft 139. The clock is supported by arms 140 and drives shaft 141 carrying cam 142. Cam 142 has two projections 143 and 144 respectively thereon. Projection 143 engages a valve 146 to allow gas to escape from space 147 and projection 144 engages valve 148 to allow gas to expand from space 136 into space 147. Gas in 147 passes through passages 149, 151 and 152 into space 132. The usual connecting means 153, 154 and 156 may be provided.

Operation of Figure 1

In the apparatus of Figure 1, part 7 is removed from part 6 and part 9 is raised up until a new

frangible pin 22 can be inserted below washer 14. 7 is then replaced in 6 and pin 22 will hold 9 in the position where arms 27 and 28 are drawn back out of positive contact with cup 34 (although cup 34 can be pushed back against the arms even in this position).

The swab 4 is then inserted in the well and lowered down through the liquid. While air or gas is in the well this gas will lift ball 21 from time to time and force up through openings 16 and out through openings 19. When liquid is encountered, liquid will flow in opening 16, lift ball 21 and pass through openings 13 and 19.

When swab 4 has reached the desired predetermined lower position its motion is reversed and it is raised. Upon raising liquid flows through 19 and 13 and places ball 21 on seat 11. Some liquid will escape around the outside between cup 34 and the wall of the well pipe but this will not occur very long because most of the liquid transmits pressure through opening 46 to space 55 throwing considerable weight on flange 36 which breaks frangible pin 22. Member 6 moves upwardly relative to member 9 into a position somewhat the same as shown in Figure 1. Arms 27 and 28 rotate and push the walls of cup 34 out into sealing relationship with the well pipe (not shown). As the well pipe increases and decreases in diameter arms 27 and 28 will move upwardly and downwardly about pivots 29 and 31 accommodating for the change in the size of pipe. Upon reaching the top of the well a new pin 22 needs to be inserted below washer 14 as described above and this cycle is then repeated.

Operation of Figure 2

Threads 63 are engaged with the cable or pipe in the same manner as threads 8 were in Figure 1, pin 88 being in place and tire 14 being deflated. Part 111 has not been employed as yet and should be disregarded for the moment. The swab 61 is inserted into the well and on the downward trip gas or liquid comes in opening 68 pushing back ball 71 and passes through 64 and out hole 66 above packer 67. Liquid flowing past 67 tends to support the same. Upon reaching the predetermined low point in the well the motion is reversed and the swab 61 is hoisted by the means attached at 63. Liquid closes valve 11 immediately and while some escapes around the outside of packer 67 the plate 102 is soon loaded with enough weight to break frangible pin 88. Upon this happening, plate 86 and all related parts move downwardly so that pin 84 opens valve 83. Gas in 79 then rushes up conduit 81 into space 77 expanding packer 76 into engagement with the wall of the pipe. If the pipe varies in diameter 67 will move inward or outward to actuate itself.

If through some trouble, the swab should become stuck in the well and it is desired to remove the same with as little effort as possible a go-devil pipe 111 is dropped down into the well where it strikes plate 97 and forces this plate to compress spring 99 and contact valve 98 allowing gas in 77 to bleed off through nipple 92 allowing packer 67 to collapse. The swab is then very easily removed.

Operation of Figure 3

Figure 3 operates much the same as Figure 2 except that the inflation of packer 124 is controlled by time clock 137. The time clock is wound up with the parts in the position shown and with packer 124 collapsed. Part 116 is secured to the usual operating means consisting of

a cable or tubing (not shown). The swab 113 is put into the well and run down to the desired position, any fluid in the well passing through 123, 122, and 119 opening valve 121 and passing out opening 126.

When a sufficient time has passed to allow the swab to be positioned properly, clock 137 rotates cam 142 until projection 144 opens valve 148. Gas from 136 passes through 148 and spaces 147 into passage 149 leading through passages 151 and 152 into space 132 in inner tube 127. Packer 124 is thus inflated.

The swab is drawn upwardly and packer 124 adjusts itself to the different diameter of the pipe.

If the swab 113 becomes stuck for any reason the operator need only wait until cam 142 rotates until projection 143 contacts 146 and opens the same, whereupon the pressure in tube 132 bleeds out through passages 152, 151, 149 and space 147, whereupon packer 124 collapses and swab 113 is easily removed from the well.

Numerous conventional changes in size, shape or arrangement of parts may obviously be made without departing from the spirit and substance of the present invention as defined in the claims.

Having described my invention, I claim:

1. A swab for operation in pipe of varying diameter in a well for swabbing liquid from said well comprising in combination a first supporting member, a second supporting member in telescopic relationship with said first member, an open top rubber cup supported on said second member, said first and second members being formed with a connecting by-pass passage communicating with said well above and below said cup, an upwardly opening check valve controlling flow of said liquid through said by-pass passage, arms pivoted to one of said members and guided during resulting pivoting movement about said pivots during telescopic movement between said members by engagement with a portion of said other member, said arms having cam surfaces disposed upon untelescoping movement of said members to move into expanding engagement with said cup, frangible means holding said members in telescoped relation and said cam surfaces of said arms out of expanding contact with said cup until broken upon raising said swab in said liquid by the weight of liquid above said cup, and spring means urging said arms into engagement with said cup.

2. A swab for operation in pipe of varying diameter in a well for swabbing liquid from said well comprising in combination a first supporting member, a second supporting member in telescopic relationship with said first member, an open top rubber cup supported on said second member, arms pivoted to one of said members and guided during resulting pivoting movement about said pivots during telescopic movement between said members by engagement with a portion of said other member, said arms having cam surfaces disposed upon untelescoping movement of said members to move into expanding engagement with said cup, frangible means holding said members in telescoped relation and said cam surfaces of said arms out of expanding contact with said cup until broken upon raising said swab in said liquid by the weight of liquid above said cup, and spring means urging said arms into engagement with said cup.

3. A swab for operation in pipe of varying diameter in a well for swabbing liquid from said well comprising in combination a first support-

ing member, a second supporting member in telescopic relationship with said first member, an open top rubber cup supported on said second member, said first and second members being formed with a connecting by-pass passage communicating with said well above and below said cup, an upwardly opening check valve controlling flow of said liquid through said by-pass passage, arms pivoted to one of said members and guided during resulting pivoting movement about said pivots during telescopic movement between said members by engagement with a portion of said other member, said arms having cam surfaces disposed upon untelescoping movement of said members to move into expanding engagement with said cup, and spring means urging said arms into engagement with said cup.

4. A swab for operation in pipe of varying diameter in a well for swabbing liquid from said well comprising in combination a first supporting member, a second supporting member in telescopic relationship with said first member, an open top rubber cup supported on said second member, said first and second members being formed with a connecting by-pass passage communicating with said well above and below said cup, an upwardly opening check valve controlling flow of said liquid through said by-pass passage, arms pivoted to one of said members and guided during resulting pivoting movement about said pivots during telescopic movement between said members by engagement with a portion of said other member, said arms having cam surfaces disposed upon untelescoping movement of said members to move into expanding engagement with said cup, frangible means holding said members in telescoped relation and said cam surfaces of said arms out of expanding contact with said cup until broken upon raising said swab in said liquid by the weight of liquid above said cup and means biasing said arms into engagement with said portion of said other member.

5. A swab for operation in pipe of varying diameter in a well for swabbing liquid from said well comprising in combination a first supporting member, a second supporting member in telescopic relationship with said first member, an open top rubber cup supported on said second member, arms pivoted to one of said members and guided during resulting pivoting movement about said pivots during telescopic movement between said members by engagement with a portion of said other member, said arms having cam surfaces disposed upon untelescoping movement of said members to move into expanding engagement with said cup, and spring means urging said arms into engagement with said cup.

6. A swab for operation in pipe of varying diameter in a well for swabbing liquid from said well comprising in combination a first supporting member, a second supporting member in telescopic relationship with said first member,

5 an open top rubber cup supported on said second member, arms pivoted to one of said members and guided during resulting pivoting movement about said pivots during telescopic movement between said members by engagement with a portion of said other member, said arms having cam surfaces disposed upon untelescoping movement of said members to move into expanding engagement with said cup, frangible means holding said members in telescoped relation and said cam surfaces of said arms out of expanding contact with said cup until broken upon raising said swab in said liquid by the weight of liquid above said cup and means biasing said arms into engagement with said portion of said other member.

7. A swab for operation in pipe of varying diameter in a well for swabbing liquid from said well comprising in combination a first supporting member, a second supporting member in telescopic relationship with said first member, an open top rubber cup supported on said second member, said first and second members being formed with a connecting by-passage communicating with said well above and below said cup, an upwardly opening check valve controlling flow of said liquid through said by-passage, arms pivoted to one of said members and guided during resulting pivoting movement about said pivots during telescopic movement between said members by engagement with a portion of said other member, said arms having cam surfaces disposed upon untelescoping movement of said members to move into expanding engagement with said cup and means biasing said arms into engagement with said portion of said other member.

8. A swab for operation in pipe of varying diameter in a well for swabbing liquid from said well comprising in combination a first supporting member, a second supporting member in telescopic relationship with said first member, an open top rubber cup supported on said second member, arms pivoted to one of said members and guided during resulting pivoting movement about said pivots during telescopic movement between said members by engagement with a portion of said other member, said arms having cam surfaces disposed upon untelescoping movement of said members to move into expanding engagement with said cup and means biasing said arms into engagement with said portion of said other member.
